DISPENSER

Edward J. Unger, Driftwood, Pa.

Application January 20, 1936, Serial No. 59,981

2 Claims. (Cl. 221—77)

The present invention relates to new and useful improvements in dispensers particularly for bottles and other containers of semi-liquids, such as ketchup, and has for one of its important objects to provide, in a manner as hereinafter set forth, novel means adapted to be conveniently mounted on the bottle or other container for forcing air thereinto in a manner to discharge the contents therefrom in a convenient and sanitary manner.

Another very important object of the invention is to provide a dispenser of the aforementioned character having an appearance which is highly suggestive of the material being dispensed. For example, if the device is intended particularly for use on ketchup bottles, said device is given the appearance of a tomato.

Still another very important object of the invention is to provide, in a dispenser of the aforementioned character, a pump adapted to force air into the bottle or other container, together with novel means for actuating said pump.

Other objects of the invention are to provide a dispenser of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a dispenser constructed in accordance with the present invention, showing the same mounted in position for operation on a ketchup bottle.

Figure 2 is a view in vertical section through the dispenser and the bottle.

Figure 3 is a view partially in side elevation and partially in section, showing the device in use.

Figure 4 is a horizontal sectional view, taken substantially on the line 4—4 of Figure 2.

Figure 5 is a fragmentary view in vertical section, showing the joint between the dispenser and the bottle.

Figure 6 is a detail view in vertical section through the air pump.

Figure 7 is a detail view in perspective of the hand lever.

Figure 8 is a detail view in elevation showing the means for detachably connecting the com-

plemental sections constituting the casing together.

Referring now to the drawings in detail, it will be seen that the embodiment of the invention which has been illustrated comprises a casing 5 which is designated generally by the reference numeral 1, said casing being of any suitable material and including complementary upper and lower half sections 2 and 3, respectively, which are detachably secured together through the medium of clips 4. Fixed on the bottom of the lower section 3 and depending therefrom is an internally threaded neck 5 which is adapted to threadedly receive the top portion of a container, such as a ketchup bottle 6. A suitable gasket 8 is provided for preventing leakage around the mouth of the bottle 6.

Extending through the casing 1 is a discharge tube 9 which is adapted to extend into the bottle 6 to a point adjacent the bottom 10 thereof. The discharge tube 9 is fixed in the lower casing section 3 at 11 in a manner to prevent leakage. The discharge tube 9 terminates in angularly extending upper and lower end portions 12 and 13, respectively. The upper casing section 2 has formed therein a centrally located opening 14 of sufficient size to permit the tube 9 to pass freely therethrough.

The reference numeral 15 designates generally an air pump which is mounted in the casing 1 by suitable means, such as a bracket 16 in the lower section 3. The pump 15 includes a cylinder 17 in which a valved piston 18 is mounted for reciprocation. A delivery tube or conduit 19, which is provided with a check valve 20, extends from the cylinder 17 through the lower casing section 3 for delivering air under pressure into the bottle 6.

The reference numeral 21 designates a lever which is pivotally mounted at an intermediate point, as at 22, in the lower section 3 of the casing 1. A connecting rod 23 couples the pump piston 18 to the lever 21 for actuation hereby. The connecting rod 23 is coupled to one end of the lever 21 by a pin and slot connection 24. The other end of the lever 21 is connected by a link 25 to the inner end of a hand lever 26 which is pivotally mounted at an intermediate point, as at 27, in the lower portion of the lower casing section 3, said hand lever 26 being operable in an opening 28 which is provided therefor in said lower casing section 3. It will be noted that the arrangement is such that the hand lever 26 extends adjacent the neck or upper portion of the bottle 6. Mounted on the hand lever 26 is a

spring 28 which is adapted to engage the bottle 6 in a manner to yieldingly urge said hand lever 26 away from said bottle.

It is thought that the operation of the invention will be readily apparent from a consideration of the foregoing. When it is desired to discharge the contents of the bottle, said bottle, with the device mounted thereon, is tilted to substantially the position shown to advantage in Figure 3 10 of the drawings. Then, by actuating the hand lever 26 the pump 15 is operated to force air into the bottle 6, said air displacing the contents of the bottle, forcing said contents out through the tube 9. When the hand lever 26 is swung toward the bottle 6 the valved piston 18 of the pump 15 moves on its power stroke. The spring 28 then returns the hand lever 26 for the next stroke. By simply removing the upper casing section 2, which constitutes a cover, access to the 20 mechanism in said casing may be had. After the bottle has been emptied the device may be readily removed therefrom and mounted on another bottle. Obviously, the invention may be mounted on different sizes of bottles or other containers 25 by simply varying the size of the neck 5.

As illustrated to advantage in Figure 1 of the drawings, the casing 1 is substantially of a shape and color similar to a tomato. Surrounding the opening 14 in the top of the casing 1 are representations of leaves 30 which are preferably colored green. The portion of the tube 9 which projects from the top of the casing 1, including the angularly extending portion 12 which constitutes a spout, is also preferably colored green in representation of a stem.

It is believed that the many advantages of a dispenser constructed in accordance with the present invention will be readily understood, and although a preferred embodiment of the device is 40 as illustrated and described, it is to be understood that changes in the details of construction and in the combination and arrangement of parts may be resorted to which will fall within the scope of the invention as claimed.

45 What is claimed is:—

1. A dispenser of the class described comprising a casing, means for detachably securing said casing on a container, a tube extending through the casing, one end of said tube being engageable

in the container for receiving the contents thereof, an air pump mounted in the casing, a conduit for conveying air under pressure from said pump into the container, and means for actuating the pump, said pump including a valved piston, said means comprising a hand lever pivotally mounted, at an intermediate point, in the casing and projecting therefrom adjacent the container, a second lever pivotally mounted, at an intermediate point, in the casing, a connecting rod coupling the piston to one end portion of the second-named lever for actuation thereby, a link connecting the hand lever to the other end of said second-named lever for actuating the same, and a spring mounted on the hand lever and engageable with the container for actuating said hand lever in one direction. 15

2. A dispenser of the class described comprising a casing, a threaded neck on said casing for removably mounting said casing on a container, said casing including complementary upper and lower half sections, means for detachably securing said half sections together, the upper half section having a centrally located opening therein, a discharge tube extending through the casing and fixed to the lower half sections, said tube extending through the opening in the upper half section, said tube including angularly extending end portion, one end portion of the tube being engageable in the container for receiving the contents thereof, a pump mounted in the lower half section, said pump including a cylinder and a valved piston mounted for reciprocation in said cylinder, a valved conduit connected to the pump for conveying air under pressure into the container, a lever pivotally mounted, at an intermediate point, in the lower half section, a connecting rod coupling the piston to one end portion of said lever for actuation thereby, a hand lever pivotally mounted, at an intermediate point, in the lower half section of the casing and projecting therefrom adjacent the container, a link operatively connecting said hand lever to the other end of the first-named lever for actuating the latter, and a spring mounted on the hand lever and engageable with the container for actuating said hand lever in one direction. 20 25 30 35 40 45
